UNITED STATES PATENT OFFICE.

JOSEPH HAJEK, OF EAST PITTSBURGH, PENNSYLVANIA.

PHONOGRAPH.

1,308,065.

Specification of Letters Patent.

Patented July 1, 1919.

Application filed December 15, 1917. Serial No. 207,334.

To all whom it may concern:

Be it known that I, JOSEPH HAJEK, a subject of the Emperor of Austria, residing in East Pittsburgh, in the county of Allegheny and State of Pennsylvania, have invented new and useful Improvements in Phonographs, of which the following is a specification.

This invention relates generally to sound reproducing machines or phonographs and has among its objects the production of a machine of this character for simultaneously reproducing a plurality of sounds independently recorded upon a single record strip.

Another object is to provide means for varying the intensity of the simultaneously reproduced sounds.

Still another object resides in the provision of a phonograph using a flexible record strip having a plurality of independent selections, and each selection being so divided that the vocal parts, and the various instrumental parts are all separately recorded but all of which are arranged for synchronous reproduction.

Other objects will be obvious from the description and appended drawings.

With these and other objects in view my invention consists in the novel construction, combination, and relative position of the parts and members shown in the accompanying drawings, hereinafter described, and particularly pointed out in the appended claim.

Referring to the drawing in which like reference characters indicate like or corresponding parts:

Figure 1 is a front elevation of a phonograph structure embodying my invention. Fig. 2 is a cross section taken on line 2—2 of Fig. 1. Fig. 3 is an end elevation of the mechanism showing the driving elements looking at Fig. 4 in direction of 3—3. Fig. 4 is a front elevation of the mechanism. Fig. 5 illustrates a cross section taken on line 5—5 of Fig. 4. Fig. 6 shows a longitudinal section through the record roller. Fig. 7 illustrates a longitudinal cross section through the receiving roller and Fig. 8 a cross section taken on line 8—8 of Fig. 7. Fig. 9, illustrates a fragment of my flexible record showing in this instance an eight selection record, the selections being lettered from *a* to *h* inclusive and for example, the piano parts indicated by *A*, the violin parts by *B* and the cornet parts by *C*. Fig. 10 is a section taken on line 10—10.

Referring to the drawings which illustrate a structure embodying my invention, I provide a suitable cabinet 10 which is preferably mounted on rollers 11 and which is provided with a sound emitting longitudinally extending opening 12 located in front of the terminals of the curved sound conveying tone-arms 13.

Between the opening 12 and the terminals of the tone-arms 13, I provide a pair of rollers 14 and 15 which are provided with the respective cranks 14^A and 15^A arranged to wind a flexible member 16 of a structure of progressively varying density from one roll 70 onto the other and vice versa. It is thus obvious that I have provided modifying means for varying the sound intensity.

The sound reproducing mechanism is preferably mounted in the center of the cabinet 75 upon the floor 17. On each side of the central mechanism compartment are compartments provided with doors 18 and 19, available for the storage of the varying sound records.

Suitably mounted on block 20 is an electric motor 21 having a shaft 22 extended on both sides thereof and carrying the rigidly mounted worm gears 23 and 24. The worm 23 is in mesh with and drives the 85 loosely mounted gear 25 counter-clockwise. This gear 25 is cast with a jaw clutch 26^A which when in mesh with the other co-operating half 26^B drives the shaft 27 upon which is mounted the solid driving roller 28 90 having near each end, circumferentially arranged teeth 29 which engage within suitable perforations in the flexible sound record indicated in Fig. 3, by numeral 30.

Each record 30, is mounted on a roller 31, 95 which roller consists of the cylindrical shell 31^A having flanged ends 31^B and being mounted upon the cylindrical spool 32 which is suitably rigidly mounted on spindle 33 having squared ends 33^A arranged for support within the spring-pressed bearings 34. Rigidly mounted to spindle 33 are the two opposed flat springs 35 which partially project through the openings 32^A to frictionally engage the inner surface of the shell 31^A to 100 thus resist the free rotation of shell 31^A upon the spool 32.

The receiving roller 31^C is similar in detail to the record roller 31 except that the shaft 36 in this case has rounded ends and 110 carries only one flat spring 35 so as to have only approximately one-half of the resist-

ance as that of the record roller 31. The purpose of this difference in resistance is obvious, for as the record 30 is driven with a constant speed by the drive roller 28, and as the record strip unwinds from roller 31, the circumferential speed of such roller 31 must slowly decrease, while as the record is steadily wound upon roller 31^c its circumferential speed increases; therefore with a higher resistance upon the feed roller 31^c the record will constantly remain taut. The shaft 36 of the receiving roller 31^c is sufficiently extended to carry the rigidly mounted sprocket 37 which is propelled by a chain 10 drive from the outer double sprocket 38, the inner integral one being propelled by a chain from sprocket 39 which is rigid on shaft 27. The double sprocket 38 is loosely mounted on a spindle or pin 40 which is rigid within the 15 upstanding leg of arm 42. It will be observed that both of the walls 41 are recessed at 41^a to permit the removal of the record roll 31 and to afford a slight swinging upward movement of the roller 31 as will be 20 hereafter explained. Each bearing 34 is loosely mounted within the angularly bent arm 42 which is pivotally mounted upon the extended end of spindle 36. One of the 25 bearings 34 carries a pinion 43 rigidly mounted upon the pin extension 34^b so as to impart clockwise motion to the roller 31 and thus rewind the record thereon. A heavy 30 spring stop 44 is mounted upon the support 20 and with a finger-like extension 44^a normally engages between the teeth of pinion 43 to prevent the rotation of spindle 33 during 35 the playing of a selection from the record roller 31. This stationary position of spindle 33 and spool 32 will cause the rotation of shell 31^a under frictional resistance of 40 springs 35.

The rewinding motion above mentioned, is transmitted to the roller 31 through the engagement of pinion 43 with the underside 45 of gear 43^a when the clutch lever 45 is raised to a position with the spring lock 46 moved with the tooth 46^a from notch *a* to *c*. The upward movement of lever 45 which is rigid with the pivotal shaft 47 will raise the pin 50 48 which is rigid with the arm 42 and which projects through the slot 45^a. It will now be observed, that simultaneously with and slightly preceding the engagement of pinion 43 with worm 24, the lower integral extension 45^b with its inwardly bent fork 45^c will disengage the clutch-half 26^b from 26^a and thus stop the rotation of the driving roller 28 to permit the reverse movement thereof. It will be noted that shaft 47 extends through to the opposite side wall 41 upon which end thereof is an angular mem-

ber 49 having a slot 49^a engaging the pin 48 of the arm 42.

The raising and lowering of lever 45 also respectively raises and lowers, in unison, the plurality of reproducer arms 50 which are rigidly mounted upon shaft 51. This movement is accomplished through the medium of shaft 52 the ends of which are rigidly mounted to the upstanding legs of the arms 42. An elongated slot 53 is cut into the walls 41 for shaft 52. The reproducers 54 are pivotally supported within the ends of arms 50 and through their movement are engaged or disengaged from the record strip 30. It may now be stated that if the lever 45 be raised into intermediate position in engagement with notch *b*, all of the reproducers 54 will be raised sufficiently to permit their lateral movement upon the rotation of the thumb nut 55 at the threaded end of shaft 51, (shown in Fig. 4) to thus change the selection to be played. It is my desire to provide a single record strip 30 which will be flexible and which will be coated with a suitable preparation into which will be cut the recorded sound vibrations but in this case, I prefer to separate all voices or instruments so that each reproducer will reproduce the individual sound vibration of either a violin, piano, vocal solo, etc. Thus it is my intention of rendering more clear and natural reproductions.

The gear 43^a is cast rigid with the pinion 24^a which is propelled by the worm 24.

I may further say that the thumb nut 55 is preferably made with numerals 56 or characters upon the rim which register with an indicator 57 to indicate the selection to be played.

It is thought that the foregoing description and illustrations clearly disclose the construction and operation of the invention, hence a more extended explanation is omitted.

I claim:—

A phonograph comprising a motor, a single flexible record having a plurality of independently recorded sound waves, means for synchronously reproducing said waves, a pair of rollers arranged to receive said record in its movement from one roller to the other, means for moving said record propelled by said motor, means for reversing the movement of said record, and means for simultaneously laterally shifting said reproducing means.

In witness whereof, I have hereunto subscribed my name this 8 day of December 1917.

JOSEPH HAJEK.
